UNITED STATES PATENT OFFICE.

VINCENT G. APPLE, OF DAYTON, OHIO, ASSIGNOR TO THE APPLE ELECTRIC COMPANY, OF DAYTON, OHIO, A CORPORATION OF OHIO.

MEANS FOR STARTING AND CONTROLLING INTERNAL-COMBUSTION ENGINES.

1,104,467.

Specification of Letters Patent.

Patented July 21, 1914.

Application filed July 22, 1912. Serial No. 710,865.

To all whom it may concern:

Be it known that I, VINCENT G. APPLE, a citizen of the United States, residing at Dayton, in the county of Montgomery and State of Ohio, have invented certain new and useful Improvements in Means for Starting and Controlling Internal-Combustion Engines, of which the following is a specification.

10 My invention relates to improvements in means for starting and controlling internal combustion engines.

One of the objects of my invention is to provide a dynamo electric machine to operate as an electric motor for starting an engine of the class described, and having capacity to generate electric current when driven by an engine, when the said engine becomes self-propelling, and a single or common instrumentality to control both the engine and the dynamo electric machine, and also to control the speed of the engine.

In automobiles that are driven by internal combustion engines, the speed thereof is controlled, in a great measure, by means, usually a lever, for advancing and retarding the spark, used for igniting the fuel charge of the engine, with reference to the time of the power stroke. In systems for automatically starting the propelling engine by electric means, notably, in my system disclosed in my co-pending application filed the 22nd day of July, A. D. 1912, which is identified by Serial No. 710,864, and my co-pending application filed the 8th day of August, A. D. 1912, and identified by Serial No.

714,086, a dynamo electric machine is employed in connection with storage batteries whereby the dynamo is first used as a motor for initially rotating the shaft of the engine until the engine becomes self-propelling, after which the dynamo electric machine operates as a generator when driven by the engine to produce electric current to charge the batteries and to supply the ignition device. In the first said application a diagrammatic representation of all of the circuits are shown, for the different phases of operation of the three power producing instrumentalities, and in the second application, a controlling switch for effectuating the conditions displayed in the aforesaid

diagrams is disclosed. In both of these applications I have referred, generally, to a "switch J" for controlling the ignition circuit. In this present application I will describe, specifically, the switch referred to and fully set out the object and use thereof.

Other and further objects of my invention will become readily apparent to persons skilled in the art, from a consideration of the following description when taken in conjunction with the drawings, wherein—

Figure 1 is a side elevation of the steering wheel and support and the spark controlling lever and connections; Fig. 2 is a broken away enlargement of the wheel, showing the lever in plan view; Fig. 3 is a side elevation of a lock for locking said lever in neutral or open circuit position; Fig. 4 shows a side elevation of the switch and connection to the spark controller or distributor; Fig. 5 is an end elevation of one of the switch terminals; Fig. 6 is a diagrammatic view of the circuits as they appear when the batteries are in series and when the dynamo is functioning as a motor, and also showing the switch J for controlling the igniting circuit, closed; Fig. 7 is an end view of my controller fully disclosed in the prior controller application, to which I have heretofore referred, showing the parts thereof in their respective positions when the circuits are as represented in diagrammatic view Fig. 6; Fig. 8 is a side elevation of a part of the said controller showing the relation of the stationary contacts and the rocking switch blades of the controller.

In all the views the same reference characters are used to indicate similar parts.

I will first describe the circuits and the parts thereof, as exemplified in diagram Fig. 6, and I will then more specifically point out the features of my improved switch operating means and its use in association therewith. Fig. 6 shows five batteries, each composed of a plurality of cells. In this instance there are three cells to each battery and the batteries are independently grouped as shown and are indicated by A, B, C, D, and E, capable of impressing a total electromotive force of 30 volts, when connected in series, and an electromotive force of 6 volts, when connected in parallel. The batteries are ca-

pable of being connected in either series or in parallel, as depends upon the intended operation of the dynamo. When the dynamo is to be started as an electric motor for initially rotating the shaft of a gas engine, the batteries are to be connected in series, as shown in the diagram, and the direction of the current through the circuits is as indicated by the arrows. Fig. 7 shows the position of the blades of the controller at the time when the batteries are connected in series. This figure only shows the end view of the controller; but mounted on the same shaft, and rotatable therewith are as many blades as are shown in the diagram for effecting the circuit arrangements shown therein. Each of the independent batteries has each of its terminals connected to two groups of switch terminals, or clips. Those on the right hand side are indicated by a, a' , b, b' , c, c' , d, d' , e and e' . There are two more similar clips and coacting switch blades, the former being indicated by f and f' . On the other side of the axis of the switch are terminals, or clips, $m, n, o, p, q, r, s, t, u, v, w$ and x . There are a corresponding number of coacting switch blades, adapted to be moved or rocked by the controller. Those on the left hand side, are indicated by reference characters 16 to 60 inclusive. When the dynamo electric machine is to be operated as a motor, by current furnished by the batteries in series, the current will pass through the following circuit: from the plus or positive terminal of battery E, over the wire 105', to the clip e' , over the wires 2, 3, 4, 5, 6, to the brush 7, of the armature A', through the armature to the brush 8, over the wire 9, through the series field winding H, to the negative terminal D² of the dynamo, and thence over the wires 10, 11, 12, 13, 14, 15, to the clip x , over the switch blade 16, through the connecting wire 17, over the switch blade 18, to the clip w , over the wire 19, to the negative terminal of the battery A, and thence to and through all of the batteries in series back to the positive terminal E plus of the battery E, thus completing the circuit and actuating the dynamo as a motor. The igniting circuit will be completed as follows: starting from the wire 105', over the wires 2, 40, through the lighting fuse L F, over the wires 41, 42, 43, 44 through the primary coil of the igniting device, over the wires 46, 46, 47, to the clip u of the switch J, and through the switch J, which is now closed, over the wires 48, 49, to the clip m , over the switch blade 50, to the wires 51, 54, 52^a, which is a common connector, and thence from 88, over wires 56, 32, blade 33, clip q , wire 34, to the negative terminal of the battery D, thus including two batteries, of 12 volts, in circuit with the primary of the igniting device, at

the time when the dynamo is operating as an electric motor. Thus it will be observed that 65 the igniting circuit cannot become operative until the switch J has first been closed.

It is customary in starting gas engines to "retard the spark" that is to say to make the spark later in point of time, in the first 70 one or two power strokes that the engine makes, than normally prevails. In the physical representation of the device J¹ is the lever that is used ordinarily to control the time at which the spark in the cylinder 75 of the gas engine is to be made, with reference to the power stroke. When the lever is moved to its extreme position indicated by S, in Fig. 2, the spark will be delayed or retarded to the greatest extent, and while the lever J¹ is in this position the controlling 80 circuit of the igniter, as shown in the diagram of circuits, is closed as at J, so as to render it necessary that the spark controlling lever should be in this retarded position to retard the spark before the circuit, controlling the spark is closed, thereby making this position of the spark-time controlling lever a condition precedent to the starting of the engine. The lever J¹ is pivoted 85 as at J², to a rod J³ which passes through a hollow post J⁴ that supports the steering wheel J⁵. The rod J³ is connected to an arm J⁶ having connected to its outer end, a link J⁷, that operates to move the spark distributor J¹⁴ for the purpose of advancing or retarding the spark, so as to control the spark-time with reference to the power stroke of the engine by the movement of the lever J¹ over the segment J⁸. These parts 90 are usual in automobile constructions. Connected to the arm J⁶ is a link J⁹. An arm J¹⁰ may be employed to rock the controller switch, which may have all of the blades and clips represented in the diagram Fig. 6, 105 or it may be made to operate the single switch J for controlling the ignition circuit only. The arm J⁶ is connected to the rocking lever J¹⁰ of the switch by means of the link J⁹, so that when the spark controlling 110 lever J¹ is shifted over the segment J⁸, the spark-time device is thereby shifted and coincidentally the switch for controlling the circuits operates to place the batteries in series with themselves and with the dynamo for 115 the purpose of operating the dynamo as a motor for starting the engine, and to place them in parallel, for the purpose of being charged by the dynamo, when the engine becomes self-propelling. When the controller 120 switch is in the position shown in Fig. 7, the batteries are connected in series and the dynamo is operating as a motor, and at that time the spark is retarded by the lever J¹ which is near the point indicated by S, and 125 the switch J, controlling the circuit contain-

ing the ignition devices, is closed. When the lever J^1 is moved to substantially the central position of the segment J^8 , the switch, as shown in Fig. 4 is open, and all 5 circuits connected thereto are open, and the engine will stop, and while in this open position the spark shifting lever J^1 may be locked, by the lock J^{11} , which shoots up a bolt J^{12} , that engages lever J^1 and prevents 10 the said lever from being moved either to the left or to the right when the bolt is in locked position. As soon as the engine begins to operate, by its own power, then the spark should be advanced and the lever J^1 15 is moved farther toward the point marked R, or running position, on the segment J^8 . At the same time the switch blades indicated by 108, as shown in Fig. 4, may be made to make contact with the corresponding 20 associate and coating clips f , whereby the batteries are placed in parallel relation with each other and with the dynamo electric machine, which now becomes a generator, and which at the same time, begins to put current into the batteries. During running 25 operation there will be considerable latitude of movement of the lever J^1 from the central, or open circuit position to the extreme position marked R, and to permit of this scope 30 of movement I make the switch blades 108 very wide, so that they may be moved in the respective clips without breaking circuit therewith, throughout the extent of movement of lever J^1 through the region described. Now it will be apparent that during 35 the time that the dynamo is being driven by the engine, as a generator, that the lever J^1 may be moved through any distance, within its normal range of movement, so as 40 to thereby vary the spark-time for the purpose of regulating the speed of the engine as usual, and at the same time the circuit connections that are necessary to connect the dynamo, as a generator, to the storage batteries in multiple, will be maintained intact, and furthermore it follows that it is essential 45 that the lever J^1 must be placed on the segment J^8 , near the point marked S and thereby retard the spark, before the igniting 50 circuit can be closed, preliminarily to starting the engine. If the lever J^1 is placed beyond the open circuit point of the segment J^8 , toward the point marked R, and attempt be made to start the engine, it will 55 then be observed that the switch J, of Fig. 6 is open and that no current will flow through the igniting circuit, and therefore, the engine cannot be started, and the circuits will be such as are required for the dynamo 60 when acting as a generator.

The switch lever J^1 will be used to control the two instrumentalities; the spark-time of the engine, and the integrity of the circuit,

containing the spark producing device in the manner heretofore described, without 65 reference to the question of whether the dynamo is to be used as a generator or as a motor, or whether a dynamo be employed at all, as the new function of the lever J^1 is quite independent of the source of current 70 for igniting the engine charge. While this might well be done to advantage, the single controlling circuit, for the igniting device, is the only circuit that must be controlled by the spark-time-controlling lever J^1 . 75

While I have herein described with considerable detail a single embodiment of my invention, it is understood that it is not to be limited further than defined in the appended claims. 80

Having described my invention, what I claim as new and desire to secure by Letters Patent of the United States is:

1. In an automobile, or similar vehicle, the combination with a spark-time-controlling device, a dynamo electric machine, a plurality of storage batteries, grouped for series and for parallel connection, a spark producing means, a circuit therefor adapted for connection with said batteries and 85 with said dynamo, a switch for connecting said batteries in series and in parallel, alternatively, with said dynamo, and for closing said spark producing circuit when said batteries are in parallel relation and an auxiliary switch for closing said circuit when said batteries are connected in series relation, and a common means for controlling said latter switch and said spark-time device. 100

2. The combination with an internal combustion engine, of a spark-time-controlling device, a dynamo electric machine, a plurality of storage batteries, grouped for series and parallel connection, spark producing means, a circuit therefor, adapted for connection with said batteries and with said dynamo, a switch for connecting said batteries in series or in parallel alternatively with said dynamo, an auxiliary switch movable in one position for closing said spark circuit when batteries are in parallel relation and movable into a second position for closing said circuit when the batteries are connected in series relation, and a common 105 means for controlling the latter switch and said spark-time device. 110

3. The combination with an internal combustion engine, of a dynamo-electric machine, a plurality of storage batteries, grouped for series and parallel connection, spark producing means, a circuit therefor, adapted for connection with said batteries and with said dynamo, a switch for connecting said batteries in series or in parallel alternatively with said dynamo, an auxiliary 115 120 125

switch movable in one position for closing said spark circuit when batteries are in parallel relation and movable into a second position for closing said circuit when the batteries are connected in series relation, and common means for controlling the said switches.

In testimony whereof I hereunto set my hand in the presence of two witnesses.

VINCENT G. APPLE.

In the presence of—
FORÉE BAIN,
MARY F. ALLEN.
